Patented Feb. 26, 1918.

UNITED STATES PATENT OFFICE.

GEORGE J. BIRNEY, OF TORONTO, ONTARIO, CANADA.

COMBINATION SHIRT AND SUSPENDERS.

1,257,450.

Specification of Letters Patent. Patented Feb. 26, 1918.

Application filed February 19, 1917. Serial No. 149,423.

To all whom it may concern:

Be it known that I, GEORGE JOHN BIRNEY, a subject of the King of Great Britain, and resident of the city of Toronto, county of 5 York, Province of Ontario, in the Dominion of Canada, have invented certain new and useful Improvements in Combination Shirt and Suspenders, described in the following specification and illustrated in the accompanying drawings, that form part of the same.

The principal objects of the invention are to provide an invisible suspender in which the fasteners for securing same to the 15 trousers will always be accessible from the outside of the shirt and which will hold the shirt securely in position without tearing or damaging same.

A further object is to provide a simple 20 form of combination suspender and shirt in which the suspender may be removed with the shirt and will be retained temporarily in positive relation therewith ready for wear and further, to allow for the ready removal 25 of the suspenders for laundrying.

The principal feature of the invention consists in arranging suspender members upon the inner side of a shirt, the tab ends thereof extending through openings in the 30 shirt and being positively held by fastening members secured to the suspender and extending through a secondary opening and forming holding loops.

In the drawings, Figure 1 is a perspective 35 view showing my improved device, the shirt being broken away to show the manner of application and the suspenders being shown partly in dotted lines.

Fig. 2 is a cross sectional view showing 40 the suspender in position embracing and holding the shirt.

Fig. 3 is a plan view of the suspender strap.

Fig. 4 is a detail plan view showing the 45 tab end of the suspender holding the shirt.

Invisible suspenders of various kinds have been placed upon the market but those forms of suspenders which have been extensively marketed and which grip the body of the 50 shirt with the buttons of the trousers have the objectionable features of being very difficult to fasten and are never secure and they are very hard on the garment, particularly as the point of connection is often too short 55 and when the wearer bends an undue strain

is placed upon the shirt which results in its being torn.

Various forms of suspenders have been devised in which the suspender straps are arranged beneath the garment and extend 60 through slots in the shirt but the means for holding the shirt in position have not been at all serviceable.

The present invention has been devised with the object in view of providing a suspender which will effectively support the trousers and will be readily accessible for adjustment or attachment and which will positively engage and hold the shirt in a definite position. To accomplish this result 70 I provide the shoulder straps 1 having suitable adjusting buckles 2 and the fastening tab ends 3 adapted to be secured to the trousers. The shoulder straps 1 are worn beneath the shirt and the shoulder portions 75 preferably slide through straps 4 arranged in the yoke of the shirt.

The body of the shirt is formed with pairs of transverse slits 5 and 6.

The tab ends 3 are adapted to be passed 80 through the slits 5 to the outer side of the shirt and are secured to the trousers.

7 are short tabs or straps secured upon the outer sides of the tab ends 3 above the button hole ends and are adapted to be passed through 85 the upper slits 6, the lower ends thereof extending beyond the cross piece 8 of the shirt between the slits and to be fastened by means of a suitable fastener 9.

When the tab members 7 are thus arranged and secured the body of the shirt will be held positively in a definite position and the upper portion above the trousers is preferably bloused as shown so as to present a neat and dressy appearance. The suspender members 1 may be readily attached to the trousers from the exterior and they may be left temporarily attached to the shirt, that is, they may remain attached to the shirt when it is taken off and intended to 90 be worn again and when again put on the fastening ends are in place for immediate connection to the trousers. The suspender members may be readily detached from the shirt to allow for the laundrying of same. 100 105

The suspender and the shirt are both very simple and the combination provides a very desired result.

What I claim as my invention is:—

1. A combination shirt and suspender, 110

comprising a shirt having transverse slits through the body portion, suspender members having fastening ends adapted to extend through certain of said slits and to be secured to the trousers, and fastening members each having one end fixed to the fastening end and adapted to have its other end temporarily secured to said fastening end, said fastening members forming loops and 10 extending through slits other than those through which the fastening ends of the suspenders extend and positively securing the shirt to the suspender end.

2. A combination shirt and suspender.

comprising a shirt having transverse slits arranged in pairs one slit being above the other in the body portion, suspender members arranged on the inner side of the shirt and having fastening ends extending through one of each of the paired slits, tab members 15 secured to said fastening ends and each extending through the adjacent slit of the pair and having the free end temporarily secured to the protruding end of the fastening member to positively hold the shirt to the suspender. 20 25

GEORGE J. BIRNEY.
